LOW PRESSURE STEAM INJECTOR

Walter Howard Tinker, Muncie, Ind., assignor to
George A. Ball, Muncie, Ind.

Application July 9, 1937, Serial No. 152,729

13 Claims. (Cl. 103—265)

This invention relates to injectors and particularly to injectors employing low pressure steam as motive fluid. Low pressure steam injectors, as now employed, utilize both high pressure and low pressure steam as motive fluid, i. e., as the medium for entraining and heating water and for delivering that water from a region of low to a region of high pressure.

In the present embodiment of my invention I also employ both high pressure and low pressure steam as the motive fluid, but an object of my invention is to so deliver these high and low pressure components of the motive fluid as to effectively employ each and thus produce an efficient and effective apparatus.

A further object is to produce an injector of the type above defined which, when associated with the boiler of a locomotive engine, for example, so utilizes the exhaust steam from the locomotive cylinders as to occasion an appreciable increase in overall efficiency of the combined unit, i. e., of the injector and the boiler.

A further object is to produce an injector in which the parts thereof are so associated and combined as to not only produce an effective and efficient injector, but one which facilitates assembly and disassembly of the parts going into the make-up thereof and which, therefore, simplifies the operation of disassembling the parts for inspection, repair or replacement purposes.

These and other objects which will be made more apparent throughout the further description of my invention are attained by means of apparatus embodying the features herein described and illustrated.

In the drawings accompanying and forming a part hereof Figure 1 is a fragmental, longitudinal, sectional view of the water and steam receiving end of an injector embodying my invention;

Fig. 2 is a corresponding view of the water delivery end of the injector illustrated in Fig. 1 and the two views, considered together, illustrate the entire injector in longitudinal section;

Fig. 3 is a transverse sectional view along the line III—III of Fig. 1;

Fig. 4 is a sectional view along the line IV—IV of Fig. 3;

Fig. 5 is a longitudinal sectional view of a water delivery cone constituting a detail of my invention and disclosing the delivery end of the cone serrated or grooved both internally and externally;

Fig. 6 is an end view of the cone shown in Fig. 5;

Fig. 7 is a fragmental sectional view on an enlarged scale of the steam nozzle 19 of Fig. 1, showing the external surface of the delivery end thereof slotted;

Fig. 8 is an end view of the nozzle shown in Fig. 7;

Figs. 9 and 10 are views corresponding to Figs. 5 and 6 but illustrating, on a reduced scale, a somewhat different form of water delivery cone and an arrangement in which the outlet end of the cone is serrated or grooved only on its inner face; and

Figs. 11 and 12 are views corresponding to views 7 and 8 but disclosing the end of the cone as notched in such a way as to provide longitudinally extending prongs on the end thereof so arranged that the spaces between the prongs produce longitudinally extending ridges or ribs on the surface of the water stream issuing from the nozzle and thus extend that surface and increase the effectiveness of the stream in receiving heat and kinetic energy from the motive fluid, i. e., for example, the steam.

The injector illustrated in Figures 1 and 2 includes the usual water and steam passages. These passages are, however, so associated that during the operation of the injector a water annulus is maintained between the high pressure motive fluid and the low pressure motive fluid and under such conditions that both components of the motive fluid simultaneously act on the water in such a way as to impart heat and longitudinal movement thereto. Another characterizing feature of my invention is that the stream of water entering the working passage of the injector is ribbed or otherwise formed so as to extend its surface and thus increase the surface of contact between the water and the motive fluid, which is hereinafter termed steam.

A further characterizing feature of the invention is the arrangement of overflow outlets provided both in the combining tubes and in the casing or shell of the injector. In the illustrated embodiment, the injector is provided with two overflow chambers, one communicating with a low pressure portion or stage of the composite combining cone and the other with a portion or stage of higher pressure. Both chambers are, however, connected together by a port, which is controlled by a non-return valve so arranged as to prevent a back flow from the high to the low pressure chamber. Communication between the second or final overflow chamber and the atmosphere is also controlled by a non-return valve which opens in response to the pressure

in the final overflow chamber, but which is provided with means for closing it and holding it in the closed position in response to the pressure developed within the delivery passage of the injector.

Thus injectors embodying my invention are characterized by the arrangement and relationship of the steam and water passages herein broadly defined and such injectors preferably include an arrangement of overflow passages and chambers such as above defined.

As illustrated, the injector is provided with a shell 10 made up in two parts 10a and 10b. This shell is provided with a water inlet port 11, a high pressure steam inlet port 12, a low pressure steam inlet port 13, an overflow port 14, and a water delivery port 15. The two parts of the shell 10a and 10b are so formed and so connected together that they provide supports for a series of water and steam delivery tubes and nozzles which constitute, in their effect and function, the water entraining passages, the combining tubes or passages and the delivery tubes or passages of the injector.

As shown, the shell encloses a water chamber 16 with which the water inlet port 11 communicates and which extends upwardly of the shell and communicates with a water delivery cone 17, which is in effect located within a low pressure steam chamber 18 and is so arranged that it is surrounded by low pressure steam admitted to the chamber 18 through the port 13. The cone 17 surrounds a high pressure delivery nozzle 19, which is axially aligned therewith and which is so located within the cone 17 that its outlet end is located adjacent to the outlet end of that cone. With this arrangement of cone 17 and steam nozzle 19, an annular water passage or nozzle 20 is provided around the steam nozzle 19 and between it and the cone 17 and this passage 20 is in open communication with the chamber 16. A low pressure steam-directing cone 21 is so formed and located within the shell that it, in effect, forms two expansion nozzles 22 and 23, each of which communicates with, and receives steam from the low pressure steam chamber 18. In the illustrated embodiment, this is accomplished by providing the larger end of the cone 21 with an annular flange 21a, which extends forwardly of the cone and with its two circular series of ports 21b constitutes a supporting cage for the cone 21.

As a matter of structural detail this flange 21a is screwed onto and supported by a primary combining cone 24 into which the steam cone 21 projects and which is concentrically arranged with relation thereto so as to provide the expansion nozzle 23. This nozzle 23 is annular in form, surrounds the cone 21 and communicates at its throat end with the low pressure steam chamber 18 through the aforementioned cage. The annular steam nozzle 22 is formed by the cones 17 and 21.

A secondary combining cone 25 is spaced from but axially aligned with the cone 24 and, like that cone, is a converging cone. This cone 25 constitutes one of three axially aligned converging cones 25, 26 and 27, each of which is spaced from the other to provide an overflow passage, but each cooperates with the others to form the main combining tube of the injector.

As shown, the cone 26 is supported in an aperture, formed in a partition 28 of the shell, and the cone 25 is supported at the inlet end thereof by means of a forwardly projecting, annular

flange 25a formed on the cone 25. The flange 25a is provided with an annular series of ports 25b so located that they establish communication between an overflow chamber 31 and the space intervening between the cones 25 and 26. The cone 27 is provided with a similar, but rearwardly extending annular flange 27a and the annular series of ports 27b formed therein communicate with the space intervening between the cones 26 and 27 and with an overflow chamber 34. The delivery end of the cone 27 (Fig. 2) is axially aligned with, but spaced from a Venturi tube 29 which extends through an aperture formed in a partition 30 of the shell and is secured to that partition. This venturi is similar to the ordinary Venturi tube usually employed in injectors, except that the converging portion thereof is relatively short and the throat is not interrupted by the provision of an overflow aperture. The cone 27, in effect, constitutes an effective part of the venturi and by being spaced from the tube 29 provides an overflow outlet space on the inlet side of the throat of the venturi.

The partition 28 is so formed that it, together with the shell 10b and the cone 24, forms the overflow chamber 31 within the shell. As shown in Figure 2, this chamber 31 is provided with an outlet port 32, which is controlled by a non-return valve 33 so arranged as to permit flow from the chamber 31 into the overflow chamber 34 but to prevent flow in the reverse direction.

The chamber 34 is formed between the partitions 28 and 30 and is provided with an overflow port 35, which is also controlled by a non-return valve 36. As shown, the valve 36 is located within a chamber or closure 37, formed by the partition 30, a partition 38, the peripheral wall of the shell 10b and the end wall 39 of the shell. This closure or chamber 37 is provided with the overflow port 14 which is in open communication with the atmosphere.

The shell portion 10b, the partition 30 and the partition 38 cooperate to enclose the water delivery chamber 40 of the injector. The water delivery port 15 communicates with the chamber 40 and the outlet end of the venturi 29 projects into this chamber. A specially formed head 41 forms a removable closure for the chamber 40 and is located opposite the partition 30, thus giving access to the interior of the chamber 40.

In the illustrated embodiment, the high pressure steam nozzle 19 receives steam from the high pressure steam inlet port 12 through a pipe 42, which is supported by the shell 10a and which in turn forms a support for the nozzle 19. In Figures 1 and 3 of the drawings I have shown the pipe 42 provided with radially projecting, longitudinally extending lugs 42a which extend beyond the delivery end of the pipe and are adapted to engage the internal surface of the water delivery tube 17 and thus support the end of the pipe 42 on the tube 17 and positively hold it in predetermined spaced relation to that tube. These lugs extend in the direction of water flow through the passage 20 and are stream-lined in that direction as shown in Figure 4.

As shown in Figure 1, the high pressure steam nozzle 19 terminates at a point somewhat in advance of the delivery edge of the cone 17. This is for the purpose of increasing the entraining effect of the steam issuing from the nozzle 19 and, as a result of this location, the nozzle 19 and the injector parts associated therewith function to some extent as an injector in

discharging non-condensable gases, such as air, and condensable vapors from the water chamber 16 during the operation of starting the injector.

The drawings (Fig. 1) also illustrate the apparatus as equipped with a steam nozzle 44 and a combination combining and diffusion cone 45. The nozzle 44 is shown screwed into a hollow boss 46 forming a part of the shell 10b, and this hollow boss is provided with a steam inlet port 46a, through which high pressure steam is delivered. As shown, the combining-diffusion cone 45 is so formed that it may be conveniently screwed into an apertured partition of the shell portion 10b, which intervenes between the water inlet 11 and the water chamber 16. The cone 45 is axially aligned with the steam nozzle 44 and is adapted to receive the stream of expanded steam issuing therefrom. For lack of a better term the combination 44-45 may be termed a lifting injector. It, however, functions as the first stage of a two stage ejector during the preliminary operation of starting the injector and while water is being drawn through the port 11 so that it may be delivered to the water chamber 16.

In connection with the preliminary operation of starting the injector it should be noted that the main injector is capable of lifting water through the port 11 and into the water chamber 16, consequently the combination 44-45 supplements this action and after water has been lifted to such a height that it partially and then wholly submerges the inlet of the cone 45, the combination 44-45 operates as an injector and delivers water to the chamber 16. Thus it is apparent that during the starting operation the steam nozzle 19 and the injector parts associated therewith function as the second stage of an ejector in that it discharges the partially compressed non-condensable gases and steam from the water chamber 16.

In Figure 1 I have also illustrated annular steam nozzle 47, which surrounds the steam pipe 42 and is located within the annular water passage communicating with the annular water nozzle 20. As there shown, the steam nozzle 47 is adapted to receive high pressure steam from a steam chamber 48 through a pipe 49, which surrounds the high pressure steam pipe 42. It will be understood that while this steam nozzle 47 may be employed simultaneously with the combination 44-45 in the operation of starting the injector, such a procedure is unnecessary except possibly in installations where water is to be lifted to unusual heights. For this reason the steam nozzle 47 may be omitted from the particular embodiment of my invention here illustrated or it may be employed as an alternative form and be utilized in place of the combination 44-45. Throughout the further description of the operation of the injector I will assume that the nozzle 47 and its connecting steam pipe 49 are omitted from the disclosure.

In starting the injector, high pressure steam is delivered to the nozzle 19 through the pipe 42 and low pressure steam is delivered to the chamber 18 through the port 13. As previously stated, the nozzle 19 and the operating parts of the injector associated therewith function, during this portion of the operation, to evacuate the chamber 16 and thus lift water into that chamber and into the water nozzle 20. However, steam may also be delivered to the nozzle 44 and under such conditions the combination 44-45 functions as the initial stage of a two stage ejector. As the water rises in the passage communicat-

ing with the water inlet port 11 it finally fills the cone 45 and the combination 44-45 is therefore gradually transformed into an elementary water injector and functions to pump water from the passage 11 to the water chamber 16. During this period in the starting of the injector the nozzle 19 and associated parts continue to function as an air and vapor ejector, with the result that the chamber 16 is rapidly filled with water due to the combined pumping action of the combination 44-45 and the ejector action of the nozzle 19 and parts associated therewith.

After water is delivered to the nozzle 20 and the main injector starts to operate as a water entraining agent the combination 44-45 may be said to function as an isolated initial stage of the main injector because it imparts some absolute pressure to the water delivered to the water nozzle 20 and thus regulates the delivery of water to that nozzle and insures the delivery of adequate water to the injector throughout the varying conditions of operation encountered by the injector.

With the arrangement of elements illustrated and described the injector is to a large extent self-regulating. It is well recognized that as the back pressure increases on a locomotive engine the rate of evaporation within the associated boiler also increases and that, therefore, the boiler requires more water. With an injector embodying my invention applied to a locomotive engine variations in back pressure on the engine occasion variations in the amount of low pressure steam delivered to the working passages of the injector, consequently as the back pressure increases the increase in the amount of exhaust steam delivered to the low pressure steam nozzles 22 and 23 induces a larger flow of water through the water nozzle 20. Conversely, as the back pressure decreases on the locomotive engine and the demand by the boiler for water decreases, the combined effect of the steam nozzles forming a part of my injector occasions a decrease in the flow of water.

In connection with this regulating function of the combination 44-45 it should be noted that the rate of water flow through the throat of the combined combining tube and diffusion nozzle 45 depends upon several varying conditions, one of which is the absolute pressure of the water within the chamber 16 and that, therefore, if the pressure of the exhaust steam within the chamber 18 is such as to induce an increase in the flow of water through the nozzle 20 the combination 44-45 will respond to this more favorable condition and increase the flow of water to the chamber 16. Conversely, a reduction in the flow of water through the nozzle 20, occasioned by a reduction in the exhaust steam pressure within the chamber 18, will contribute to a reduced flow of water through the tube 45. Thus it is apparent that the injector is to a large extent self-regulating and that the combination 44-45 functions largely as a regulating stage of the main injector because it controls delivery of water to the chamber 16 in response to the varying conditions within the main injector.

It will be understood that the steam nozzle 19 is so designed as to expand the steam received by it to substantially the fluid pressure desired to be maintained within the associated working passages during normal operating conditions of the injector. It will also be understood that the cone 21 is so formed, with relation to associated parts (external surface of cone 17 and internal surface 75

of cone 24), that the low pressure steam nozzles 21 and 23 likewise expand the low pressure steam delivered to them to about the desired fluid pressures maintained within the inlet end of the combining tube.

The degree of expansion of both the high pressure and the low pressure steam will be determined by the initial pressure of the steam as it is delivered to the expansion nozzle and by the pressures in the working passages of the injector during normal operating conditions. Each expansion nozzle should, therefore, be proportioned so that the steam issuing from it is neither materially over nor under expanded. Where the steam is under expanded by the expansion nozzle it issues therefrom with an explosive effect and thus to some extent destroys the directional effect of the steam and renders the steam less effective as an entraining medium. Over expanding the steam within the expansion nozzle has a similar effect, in that it also tends to set up eddy currents or turbulence within the stream of steam and thus the kinetic energy in the form of velocity which is developed by the expansion of the steam, cannot be as effectively employed in imparting directional velocity to the water.

In designing both the high pressure and low pressure steam delivery nozzles it must be borne in mind that the kinetic energy in the form of velocity can be most effectively employed where each stream issuing from a nozzle not only moves in a non-turbulent stream, but in a stream in which all particles of steam move in substantially parallel lines and in substantially the direction the water must move through the working passages of the injector. In addition, the steam nozzles and the water delivery nozzle must be so arranged as to avoid substantial shock and rebound at the instant of impact between steam particles and the water.

I have discovered that the kinetic energy, rendered available by the expansion of the steam, can be most effectively employed where the water is so introduced that it is maintained in a solid or well defined stream, as distinguished from a moving mass of separate drops or spray. On the other hand, I have discovered that the energy of the steam—including energy in the form of heat—can be most effectively transferred to the water where conditions are such that the surface of the water stream is somewhat extended by forming ribs or ridges thereon which extend in the direction of the water flow. For this reason, I so form the water delivery nozzle that it produces longitudinally extending surface ribs or ridges on the water stream, but at the same time avoids breaking the stream, or any part of it, into a mass of separate drops or sprays.

I have also discovered that the best results are accomplished in an injector such as here contemplated, i. e., one employing both high pressure and low pressure steam as motive fluid, where the high pressure steam is segregated from the low pressure steam and delivered to the working passages of the injector without having first been mixed with the low pressure steam. In order to derive this advantage I have so located the water delivery nozzle 20 that the stream of water issues therefrom in the form of an annulus and I then so deliver the motive fluid that the steam from one source is delivered exteriorly of the annular stream, whereas the steam from the other source is delivered into the hollow interior of the water stream. In this

way I not only segregate the high pressure steam from the low pressure steam prior to delivery to the working passages of the injector, but I also segregate the steam from the two sources after delivery to the working passages and the annular wall of the water stream constitutes the segregating medium.

In the present embodiment of my invention steam from the high pressure source is delivered to the interior of the hollow stream of water issuing from the nozzle 20, and consequently steam from the low pressure source is delivered to and around the external surface of this annular water stream. I also so form the water delivery nozzle 20 that the surface of the annular stream is corrugated or ribbed by the delivery edges of the water nozzle, and in such a way as to materially extend that surface but at the same time avoid the formation of sprays in appreciable amounts.

The foregoing discussion discloses that the steam and water nozzles must be so positioned as to minimize shock at the time of impact between steam and water. This primarily involves the angles at which the steam is delivered from the steam nozzles and it will be apparent that the ideal situation is to so deliver the steam from each such nozzle that while each particle of steam moves toward the water stream, nevertheless steam and water move in substantially parallel lines. This ideal situation, however, cannot be attained under practical operating conditions but I have discovered that the angle of incidence (at the time of steam and water contact) should not be greater than eight degrees in order to obtain the best results.

Where a low pressure steam injector is employed in delivering feed water to a boiler, such as the boiler of a locomotive engine, the efficiency of the combined unit is increased somewhat by the amount of low pressure steam utilized as motive fluid for the injector, since such steam is ordinarily wasted. It is, therefore, desirable to design the working passages and the steam delivery nozzles of the injector so as to utilize in the injector a substantial portion of the low pressure steam rendered available during average operating conditions of the locomotive. As heretofore made apparent, my invention also involves the use of high pressure steam as motive fluid for the injector and the high pressure steam contributes to the effectiveness of the injector operation. It is, therefore, apparent that in designing the injector the nozzle areas must be so proportioned, as between high pressure and low pressure steam, as to render steam from both sources highly effective. The injector illustrated is primarily for use in connection with locomotive engines and where the boiler pressure of the associated boiler ranges from about 150 pounds to 200 pounds gage the effective throat of the high pressure steam nozzle is about one-twentieth of the effective throat of the combined low pressure steam nozzles 22 and 23. Where, however, the gage pressure of the associated boiler is higher—for example, from 350 to 400 pounds—a slight decrease in this ratio will produce more effective results. For example, where the boiler gage pressure is 400 pounds the effective throat of the high pressure steam nozzle should be about one-fifteenth of the effective throat of the combined low pressure steam nozzles. By thus proportioning the effective throats of the nozzles I proportion the amount of high and low pressure steam delivered to the injector.

After the water chamber 16 is filled with water, to the extent that the inlet to the water passage or nozzle 20 is completely filled, the water issuing from the water nozzle 20, in the form of an annular stream, is subjected on its inner surface to the action of the steam issuing from the nozzle 19 and on its outer surface to the action of the steam issuing from the annular nozzle 22. As a result of this combined action of steam from the two sources, the water is propelled axially of the working passages of the injector or axially of the various cone shaped members which constitute the combining tube of the injector.

It is apparent from the drawings that the cone 21 not only acts in conjunction with the cones 17 and 24 to form the steam expansion nozzles 22 and 23, but that the internal surface of the delivery or rear end of this cone also functions as a combining cone. The water issuing from the nozzle 20 is thus impelled through the cone 21 while retained in the form of an annular stream, and the trailing internal surface of the cone tends to gradually direct the flow of steam from nozzle 22 against the external surface of the annular stream 25 of water and also tends to compact the combined or combining streams. Upon issuing from the cone 21, the external surface of the annular water stream is subjected to the action of the annular jet of steam issuing from the expansion nozzle 23. The rear or delivery end of the cone 24 projects beyond the cone 21 and thus beyond the portion thereof which constitutes a part of the expansion nozzle 23, and it therefore may be said that this portion of the cone 24 constitutes a part of the combining tube of the injector. The tube 24 is of slightly less diameter at its outlet end than the inlet of the tube 25 and is spaced from that tube so as to provide a free overflow of spillway for the water, and this spillway communicates directly with the chamber 31.

Thus it is apparent that upon starting the injector, the water issuing from the nozzle 20 is simultaneously acted upon by the high velocity steam issuing from the steam nozzles 19, 22 and 23 and that a spillway is provided at the end of the conical member 24 in order that the water may freely flow toward the overflow 14 of the injector during the interval necessary to develop sufficient velocity energy in it to carry all of it through the combining cone 25. A second spillway is provided between the conical members 25 and 26 in order to minimize resistance to water flow or to facilitate imparting impelling velocity to the water during the initial period of starting the injector. The outlet end of the tube 25 is of slightly less diameter than the inlet of tube 26. The overflow or spillway between the conical members 25 and 26 also communicates with the chamber 31 and such water as spills through it during the starting period, collects in the lower portion of the chamber 31 and moves from that chamber through the one-way or check valve 33 and into the chamber 34.

The combining tube is also so formed as to provide two additional spillways, each of which communicates with the chamber 34. One such spillway is provided between the conical members 26 and 27 and the final spillway is located adjacent to the throat of the diffusion or Venturi tube 29 and, as illustrated, between the delivery end of the conical member 27 and the inlet end of the Venturi tube 29. In each case the outlet end of the cone ahead of the spillway is of slightly less diameter than the inlet end of the following cone.

Water delivered to the chamber 34 from the

spillways directly communicating with that chamber and from the chamber 31 is delivered to the injector overflow 14 through the valve 36, which is free to open in response to pressure within the chamber 34, except as controlled by the plunger 5 51, as will hereinafter be described. From the foregoing it will be apparent that spillways are formed at short intervals along the combining tube and that the arrangement of these spillways is such as to facilitate the rapid building up of 10 velocity energy in the water to such point where it can be delivered to the boiler after traversing the diffusion tube 29. In addition, the valves 33 and 36 are so arranged that they will successively close off communication between the chambers 31, 15 20 and 34 and the overflow 14 as normal operating pressures are reached and established within the combining tube. That is to say, after the water issuing from the nozzle 20 has acquired sufficient velocity to carry all of it past the spillways communicating with the chamber 31, the valve 33 will close the port 32 and thus close off communication between the chamber 31 and the chamber 34, and consequently between the chamber 31 and the atmosphere. This tends to maintain the desired 25 or normal operating pressure within the chamber 31 and also prevents pressures within the chamber 34 influencing or upsetting conditions established within chamber 31 and the communicating portions of the combining tube. 30

The spillways communicating directly with the chamber 34 will, in effect, be in open communication with the atmosphere through the overflow port 14 until normal operating conditions are reached within the chamber 40. This, of course, 35 means that these spillways and the chamber 34 will be in open communication with the overflow port 14 until the velocity of the water traversing the combining tube is sufficient to cause all of it to enter and pass through the diffusion tube 29. 40 Diffusion tube 29 is so designed as to convert the velocity energy of the water into pressure and sufficient pressure to cause the water to enter the boiler through the port 15, which, as illustrated, is controlled by an outwardly opening check 45 valve 52.

During the period of starting the injector and during normal operating conditions the steam is so delivered to the working passages of the injector as to tend to hold the water in annular 50 form, with the result that the water stream is subjected to the impelling as well as the heating effect of steam delivered from both sources during some portion of its travel through the combining tube. The areas of the various tubes 21, 25, 26 and 27 are so proportioned that the water entering through the nozzle 20 is maintained in the form of an annular stream, having a core of steam, from the water delivery nozzle 20 throughout the major portion of the combining tube and in this way the water is subjected to the impelling 55 effect of a confined stream of steam during a larger part of its movement through the converging portion of the working passages of the injector. For this reason steam from the high pressure source is delivered to the interior of the annular stream of water. Under normal working conditions of the locomotive engine and the injector, the steam delivered by the nozzle 19 will contain more energy, per pound, than the steam 60 delivered through the combined nozzles 22 and 23, and thus the impelling effect may be continued for a longer period and throughout a greater range of travel of the water than is possible in connection with the steam from the low 65 70 75

pressure source. Then too, the angle of divergence between the path of travel of the steam issuing from the nozzle 19 and the path of travel of the internal surface water is less than is the case in connection with the steam delivered to the external surface of a water stream, and the result of all this is that the interval (measured in period of water travel) during which water is being impelled and during which it is taking up heat from condensing steam is greatly increased by employing the annular jet of water and by delivering steam to the interior of the annular water stream.

In addition, the annular water stream increases the effectiveness of the injector by reason of the fact that the water is retained in a consolidated stream, but at the same time exposes a large surface to the motive steam. This not only increases the effectiveness of the injector from the standpoint of heat transfer from the steam to the water, but it also increases its effectiveness from the standpoint of the transfer of the velocity energy of the steam to the water, and thus makes it possible to effectively move large volumes of water.

In this connection, it will be noted that by maintaining the water in the form of a gradually converging annular stream, the steam issuing from the expansion nozzle 19 may be directed axially of the combining tube and at the same time be effectively employed as an impelling medium for the water. This is also to some extent true of the steam issuing from the expansion nozzles 22 and 23. In connection with these nozzles it will, however, be apparent that the external surface of the annular water stream is gradually decreasing in diameter along the combining tube and that, therefore, the steam issuing from the nozzles 22 and 23 is directed inwardly with relation to the axis of the combining tube. This angle of steam delivery is, however, slight when measured from the external surface of the annular stream, with the result that each steam particle issuing from either the nozzle 22 or the nozzle 23 is traveling in substantially the same direction as the water at the instant of impact between steam and water. Thus it is apparent that there is little or no tendency to set up turbulence in the streams of steam issuing from either of the nozzles 22 or 23. This is also true of the steam issuing from the nozzle 19.

In the drawings I have shown the tube 26 provided with an annular series of forwardly inclined vapor entraining apertures 53. These apertures extend through the nozzle 26 and thus communicate at their outer ends with the chamber 31 and at their inner ends with the interior of the combining cone. The inclination of these apertures is such that there is little or no tendency to spill water through them, even during the period of starting the injector. The movement of the water or the combining stream of steam and water past their inner ends, occasions an injector action and thus tends to supplement the effect of the spillways between the nozzles 24 and 25 and the nozzles 25 and 26 in withdrawing ambient air and vapor from the chamber 31. It will, of course, be apparent that the injector effect of each spillway is accentuated by reason of the fact that the outlet end of the leading cone associated with the spillway is of slightly less diameter than the inlet end of the associated or cooperating trailing cone.

The cone 27 is also provided with an annular series of vapor entraining apertures 53' which

communicate with the chamber 34 and which supplement the vapor entraining effect of the spillway provided between the cones 26 and 27 and between the cone 27 and tube 29.

The valve 36 is adapted to be closed and held closed by the pressure in the outlet chamber 40 when that pressure has reached the predetermined pressure to which the water is to be raised by the injector action. For this reason the valve 36 is provided with a closing cam 36a, which is adapted to be engaged by the plunger 51 as the plunger moves to close the valve. The plunger 51 is operatively connected to a piston 51a located in a cylinder 51b. The plunger 51 projects through and is guided by an aperture formed in the end of the cylinder 51b adjacent to the valve 36 and is surrounded by a coil spring 51c which operates between that end of the cylinder and the piston 51a and, therefore, normally tends to retract the plunger 51. The end of the cylinder 51b remote from the valve 36 is in open communication with the chamber 40 through suitable ports and piping 51d, with the result that pressure developed within the chamber 40 tends to move the piston 51d to advance the plunger 51 and thus close the valve. The strength of the spring 51c is so proportioned that this movement will not be completed until the pressure within the chamber 40 has arrived at a pressure slightly above boiler pressure.

The cam 36a is so formed and positioned that its active face lies adjacent to the retracted plunger 51 when the valve is fully open. In addition, the contour of the active face of the cam is such that as the plunger advances to close the valve, the face of the cam readily slides under the plunger and finally provides a seat for the plunger, which extends substantially at right angles to the axis of the plunger when the valve is closed.

With this arrangement the valve 36 is automatically closed when the desired pressure is established within the chamber 40. As has been said, this shuts off communication between the chamber 34 and the atmosphere. Under such conditions the injector action, above referred to, reduces the pressure within the chamber 34 substantially below atmospheric pressure and to a pressure corresponding somewhat to the pressure existing within the combining tube at the spillway between the tubes 27 and 29. The closing of the valve 36 segregates the chamber 34 from the chamber 31 and thus the desired pressure is maintained within both these chambers, with the result that the tendency of the injector to "break", after it is in normal operation, is greatly minimized.

In the drawings, I have also illustrated means for manually closing the valve 36. As there illustrated, the head 51e of the cylinder 51b is provided with an internally threaded aperture which receives the threaded end of a rod 54. The rod passes through a suitably packed gland 55 and is provided at its outer end with a hand wheel 54'. A pad 54a is swiveled or otherwise suitably connected to the inner end of the rod 54 and is adapted to engage the piston 51a when the hand wheel 54' is turned to move the rod inwardly. This pad also forms a stop for the piston 51a and the throw of the rod is such that the valve 36 may be closed and held to its seat by turning the hand wheel.

During the operation of the injector the supply of low pressure steam, as well as high pressure steam, must be maintained substantially con-

stant. For this reason some means, such as an ordinary reducing valve, is provided for delivering steam from a high pressure source to the low pressure steam chamber 18 when the pressure within that chamber falls below a predetermined point. That is to say, means are provided for augmenting the supply of low pressure steam and thereby maintaining a substantially constant steam pressure within the chamber 18 independently of variations in the amount of steam exhausted from the locomotive, and where no exhaust steam is available then the entire supply of low pressure steam is received from a high pressure source through the reducing valve. It should, however, be noted that the reducing valve here mentioned should be so adjusted that variations in back pressure on the locomotive, during average operating conditions, will occasion variations in pressure within the chamber 18 so as to obtain the self-regulation heretofore commented upon.

In Figs. 5 to 10, inclusive, of the drawings, I have shown several ways of extending the surface of the annular water stream by forming longitudinally extending ribs thereon. In Figs. 5 and 6 I have shown the cone 17 on an enlarged scale and the outlet end is there shown as provided with longitudinally extending grooves 55 and 56 formed on the external and internal surfaces of the cone at the outlet end thereof.

The grooves 56 located internally of the member 17 extend axially of the member and consequently axially of the assembly of conical members which constitutes the combining tube of the injector. It is apparent from the drawings that the internal surface of the member 17 and the external surface of the steam nozzle 19 give form to the water stream issuing from the nozzle 20 and that, therefore, the longitudinal extending grooves or corrugations provide surface extending ribs or ridges on the external surface of this annular water stream. These ribs or ridges necessarily extend in the direction of water flow and consequently longitudinally of the stream. They are spaced apart a distance corresponding to the spacing of the grooves 56 and consequently valleys or depressions intervene between them, thus producing an external surface on the stream which is in effect corrugated longitudinally of the stream.

My invention also contemplates forming such corrugations on the internal surface of the water stream and in Figs. 7 and 8 I have shown an enlarged view of the high pressure steam nozzle 19 provided with grooves 56' formed on the outer peripheral surface and at the delivery end thereof. These grooves correspond in function to the slots 56 of the tube 17 and form surface extending ribs or ridges on the inner face of the annular water stream. These ribs or ridges also extend in the direction of the water flow and consequently longitudinally of the stream.

Similar surface extending grooves may also be formed on intermediate conical members included in the make-up of the combining tube. That is to say, the outlet end of both the tubular members 25 and 26 may be provided with grooves corresponding to the grooves 56 of the tubular member 17 and these grooves will re-establish the surface extending ribs on the outer surface of the water stream.

The grooves 55 formed on the outer surface of the tubular member 17 are located within the confines of the steam nozzle 22. They, therefore, have the effect of extending the inner sur-

face of the annular steam jet issuing from that nozzle and they insure the delivery of steam to the valleys or depressions located between the ribs or corrugations formed on the external surface of the water stream. It is, of course, apparent that the conical member 21 may be provided with slots corresponding to the slots 16 and having a corresponding function.

In Figs. 9 and 10 I have shown, on a somewhat reduced scale, a modified form of water delivery nozzle 57 in which the internal surface of the delivery end of the nozzle is grooved to form the slots 58. Figs. 11 and 12 disclose a water nozzle corresponding to that illustrated in Figs. 9 and 10, but here the delivery end of the nozzle is slotted to provide a series of notches 58' which correspond in effect and in function to the grooves 56 of Figs. 5 and 6. It will be apparent that the outlet edges of the cones 25 and 26 of the injector illustrated may be similarly formed to provide the longitudinally extending serrations in the surface of the water stream.

The removable head 41 of the shell portion 10b not only provides access into the chamber 40, but also facilitates the operation of securing the tube 29 in place within the shell portion 10b. That is to say, the removable head 41 facilitates the operation of assembling and disassembling the working parts of the injector insofar as the tube 29 is concerned. By dividing the shell portion 10b into the two parts, 10a and 10b, the operation of assembling or disassembling the other working parts of the injector is materially simplified. The drawings make it apparent that the tubular member 17, the steam nozzle 19 and the steam pipe 42 are all mounted on and secured to the shell portion 10a. It will be noted that the shell portion 10a is provided with an annular flange 57' which projects into the lower pressure steam chamber 18 when the shell parts are assembled and which provides a support for the tubular member 17. As shown, the tubular member 17 is secured to the flange 57' by means of a cylindrical member 57a externally threaded at one end and internally threaded at the other. This cylinder member 57a may be formed as a unitary part of the tubular member 17 and when so formed the tubular member is then secured directly to the shell section 10a.

The drawings disclose the conical member 24 screwed into a tapped aperture formed in a partition wall 60 of the shell section 10b and that the tubular member 21 is secured by means of screw threads to this member 24. The drawings also disclose that the aperture of the partition wall 60, into which the member 24 is fitted, is of such diameter as to permit the introduction therethrough of the assembly comprising the tubular members 25, 26 and 27. Thus it is apparent that those members are not only introduced through the aperture of the partition 60, but are also secured in place on the partition 28, by reason of access made available by the aperture in partition 60. The assembly of elements including the tubular members 21 and 24 are secured in place on the shell section 10b after tubes 25, 26 and 27 are in place and all parts are thus in working position when the shell section 10a is fitted on and secured to the shell section 10b. It will also be apparent that the parts referred to as working parts of the injector may all be adjusted longitudinally with relation to each other by reason of the fact that they are fitted in place by means of screw threads. This is particularly apparent in connection with the steam

nozzle 19, the position of which can be readily adjusted, with relation to the outlet end of the tubular member 17, by merely changing its longitudinal position with relation to the steam delivery pipe 42.

From the foregoing description it will be apparent that the present invention involves an association of certain special structural parts and the following individual features, viz., delivering the water to the working passages of the injector in the form of an annular stream; maintaining the water stream in annular form during the greater portion of its travel through the combining tube; delivering impelling steam from two sources of supply and so that the internal and the external surfaces of the annular water stream are both subjected to the impelling and heating effect of steam; employing the water stream as a segregating medium between the steam jets supplied from the two sources; extending the surface of the water stream by providing thereon longitudinally extending ribs or ridges; so delivering the steam from both sources as to avoid shock at the instant of contact between steam and water and so as to avoid turbulence in both the steam and water; maintaining a core of steam within the water stream throughout the major portion of its travel through the combining tube; employing a plurality of spillways along the length of the combining tube; employing a plurality of overflow chambers, each communicating with one or more such spillways; providing separate means for closing off communication between each such chamber and the atmosphere; providing vapor entraining apertures at spaced points along the combining tube for augmenting the ejector effect at the spillways; and so forming the injector casing or shell that the working parts can be readily assembled and adjusted and can be readily disassembled or replaced.

Other advantageous structural and functional features will be apparent to those skilled in the art and it will also be apparent that various changes, additions, omissions and substitutions may be made in the apparatus without departing from the spirit or scope of the invention as defined by the appended claims.

What I claim is:

1. A method of delivering water into a boiler, which consists in creating a flow of water in the form of an annular stream, subjecting such stream to the impelling action of condensable motive fluid moving at a high velocity and surrounding such stream, simultaneously subjecting such stream to the impelling action of a condensable motive fluid delivered to the interior thereof and moving at a velocity substantially greater than that of the motive fluid surrounding said stream, gradually contracting said stream while combining it with such motive fluid by condensation thereof and while maintaining its annular form and the flow of high velocity motive fluid throughout the hollow interior thereof, consolidating said annular stream into a solid stream moving at a high velocity, converting the kinetic energy thereof into potential energy in the form of pressure and delivering such water to a boiler under such pressure.

2. A method of delivering water from substantially atmospheric pressure into a region existing at a pressure substantially above atmospheric pressure, which consists in creating a flow of water in the form of a confined, directed stream at a pressure approximating atmospheric pressure, projecting such stream beyond its con-

fining and directing walls in the form of an annular stream and substantially simultaneously subjecting it to the impelling action of an internal and external stream of a condensable motive fluid moving at a high velocity in substantially the direction of such flow, gradually contracting said stream while maintaining an internal core of such high velocity motive fluid and while combining it with such motive fluid by the condensation thereof, consolidating said hollow stream of water into a solid stream moving at a high velocity, converting the kinetic energy of said consolidated water stream into potential energy in the form of pressure, and delivering the water thereof to such region of high pressure by reason of such potential energy.

3. A method of delivering water from substantially atmospheric pressure into a boiler existing at a pressure substantially above atmospheric pressure, which consists in creating a flow of water in the form of a confined, directed, annular stream at a pressure approximating atmospheric pressure, projecting such stream beyond its confining and directing walls, in the form of an unsupported annular stream, subjecting the interior and exterior of said annular stream to jets of motive fluid moving at a high velocity in the direction of such stream and applied to said stream at points substantially equally spaced from such confining and directing walls, gradually contracting said annular stream while combining it with such motive fluid by condensation of the fluid and while maintaining the annular form thereof and the flow of such high velocity motive fluid throughout its hollow interior, consolidating said annular stream into a solid stream of water moving at a high velocity and substantially simultaneously with such consolidation occasioning a gradual transformation of such velocity energy into potential energy in the form of pressure, and delivering such water to the boiler under such pressure.

4. A method of delivering water into a steam boiler while the same is under pressure, which consists in creating a flow of water at substantially atmospheric pressure and in the form of a confined and directed stream, projecting such flow beyond its confining and directing walls in the form of an annular stream, simultaneously subjecting the interior and exterior of such stream to the impelling action of separate jets of steam moving at different velocities in substantially the direction of said stream flow, gradually contracting said stream while combining it with steam from both such jets, converting the velocity energy of said stream into potential energy in the form of pressure and delivering said stream to a boiler by reason of such pressure.

5. A method of delivering water into a steam boiler while the same is under pressure, which consists in creating a flow of water at substantially atmospheric pressure in the form of a confined and directed stream, projecting said stream in the form of an unsupported annular stream, subjecting the exterior and the interior of said annular stream to the impelling action of jets of steam moving at different velocities in substantially the direction of said stream and simultaneously applied to said stream at substantially coincident points along its length, gradually contracting said stream while maintaining its annular form and such steam flow along the interior thereof and while combining such stream and steam by condensation of the steam, then consolidating such annular stream into a solid

stream of water moving at a high velocity, converting the kinetic energy of said consolidated stream into potential energy in the form of pressure, and delivering the water thereof into such boiler under such pressure.

6. A method of delivering water into a steam boiler while the same is under pressure, which consists in creating a confined, directed flow of water existing at substantially atmospheric pressure, projecting such flow in the form of an unsupported annular stream, simultaneously subjecting the exterior of said stream to the impelling action of an annular jet of steam moving at a high velocity in substantially the direction of said stream and the interior of said stream to the impelling action of a jet of motive fluid moving at a velocity in excess of that of said annular jet, gradually contracting said annular stream of water while maintaining therein a core of such high velocity steam, consolidating said annular stream into a solid stream moving at a high velocity, converting the velocity energy of said stream into potential energy in the form of pressure, delivering the water of said stream to said boiler by reason of said pressure, and varying the rate of such delivery in response to variations in the rate of delivery of steam in such annular jet.

7. A method of delivering water into a steam boiler while the same is under pressure, which consists in expanding steam from a low pressure source to a substantially lower pressure and delivering such steam so expanded in the form of a unidirectional jet, expanding steam from a high pressure source to a pressure substantially equal to the expansion pressure of the steam from the low pressure source and delivering such steam so expanded in the form of a unidirectional jet and in a direction substantially parallel to the direction of said first mentioned jet, projecting a stream of water between such jets so that both such jets are effective in exerting a propelling force on said stream at points substantially coincident therewith, then converting the velocity energy of the water of such stream into potential energy in the form of pressure, and delivering such water to a boiler by reason of such pressure.

8. A method of delivering water from substantially atmospheric pressure into a boiler existing at a pressure substantially above atmospheric pressure, which consists in expanding steam from a high pressure source to a sub-atmospheric pressure and delivering the steam so expanded in the form of a unidirectional jet, expanding steam from a low pressure source to a sub-atmospheric pressure substantially equal to said first-mentioned sub-atmospheric pressure, and delivering the steam so expanded in the form of a unidirectional annular jet surrounding said first mentioned jet and moving in substantially the direction thereof, projecting a flow of water in the form of an annular stream between said jets so that such stream is simultaneously acted upon by said jets and at points substantially co-incident along its length, gradually combining said stream with steam of said jets while maintaining it in annular form, consolidating the annular stream into a substantially solid water stream, converting the velocity energy thereof into potential energy in the form of pressure and delivering such water to a boiler by reason of such pressure.

9. A method of delivering water into a steam boiler while the same is under pressure, which consists in creating a flow of water at substantially atmospheric pressure in the form of a directed stream, projecting said stream as an unsupported

flow in the form of an annular stream, simultaneously subjecting the exterior of such annular stream to the impelling action of steam from a low pressure source moving at a high velocity, subjecting the interior of said stream to the impelling action of steam from a high pressure source moving at a velocity in excess of the velocity of the steam from the low pressure source, gradually contracting said annular stream of water while combining it with steam from both such sources and while maintaining its annular form, consolidating said stream into a substantially solid stream, then converting the velocity energy thereof into potential energy in the form of pressure, delivering the water of said stream to a boiler by reason of such pressure and varying the rate of such delivery in response to variations in the impelling effect of steam from said low pressure source.

10. In combination in an injector, means for creating a flow of water in the form of an unsupported annular stream, means for substantially simultaneously subjecting the interior and the exterior of said stream to jets of motive fluid moving at high but different velocities in the direction of such flow and at substantially identical points along said stream, means for gradually contracting said stream while maintaining a substantial core of high velocity motive fluid on the interior thereof, means for consolidating the annular stream into a solid stream and a diffusion tube for receiving the consolidated stream.

11. In combination in an injector, an annular water passage, an expansion nozzle surrounded by said passages and terminating at a point adjacent the outlet end thereof, means for connecting said nozzle to a source of high pressure steam, an annular expansion nozzle surrounding said passage and terminating at a point adjacent the outlet end thereof, means for connecting said annular nozzle to a source of low pressure steam, means for creating a water flow through said passage in the form of an annular stream, aligned combining tubes for receiving and consolidating said annular stream and a diffusion tube for receiving the consolidated stream.

12. In combination with the sectional combining tube and the diffuser tube of a steam actuated injector, an expansion nozzle, an annular water passage and an annular expansion nozzle all arranged in concentric relationship, all terminating in substantially the same plane transverse to the line of flow therethrough and all axially aligned with said combining tube, means for delivering steam from one source and at one pressure to one of said expansion nozzles, means for delivering steam from another source at a different pressure to the other of said expansion nozzles and means for delivering water to said passage.

13. In an injector, two expansion nozzles and an annular water passage arranged in concentric relationship with the delivery edges thereof, terminating in substantially a single plane transverse to the line of flow therethrough and with one such expansion nozzle surrounded by and the other such nozzle surrounding said annular passage, means for delivering steam from a high pressure source to the inner of such nozzles, means for delivering steam from a low pressure source to the outer of such nozzles, means for delivering water to said passage, a combining tube receiving water and steam delivered from said concentric assembly and a diffuser communicating with said tube.
